US00D748170S

(12) **United States Design Patent**
Velozny

(10) **Patent No.:** **US D748,170 S**
(45) **Date of Patent:** **** Jan. 26, 2016**

(54) **CONNECTOR FOR CONSTRUCTION DRILLING CUP**

(71) Applicant: **Nir Velozny**, Tel Aviv (IL)

(72) Inventor: **Nir Velozny**, Tel Aviv (IL)

(**) Term: **14 Years**

(21) Appl. No.: **29/491,849**

(22) Filed: **May 27, 2014**

(30) **Foreign Application Priority Data**

Nov. 27, 2013 (IL) 54820

(51) **LOC (10) Cl.** **15-09**

(52) **U.S. Cl.** **D15/139; D15/133**
USPC **D15/139; D15/133**

(58) **Field of Classification Search**

U.S. Appl. No. 29/491,849, Mark Goodwin.*

Primary Examiner — Mark Goodwin

(57) **CLAIM**

The ornamental design for a connector for construction drilling cup, as shown.

DESCRIPTION

FIG. 1 is a right view of a connector for construction drilling cup showing my new design;

FIG. 2 is a left view thereof;

FIG. 3 is a front view thereof;

FIG. 4 is a back view thereof;

FIG. 5 is a perspective view thereof; and,

FIG. 6 is a perspective thereof.

1 Claim, 6 Drawing Sheets
